UNITED STATES PATENT OFFICE.

THOMAS LUND, OF BEVERLY, MASSACHUSETTS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

SHOE-SOLE AND PROCESS OF MANUFACTURING SAME.

1,282,253.

Specification of Letters Patent. Patented Oct. 22, 1918.

Application filed February 3, 1917. Serial No. 146,494.

To all whom it may concern:

Be it known that I, THOMAS LUND, a citizen of the United States, residing at Beverly, in the county of Essex and State of Massachusetts, have invented certain Improvements in Shoe-Soles and Processes of Manufacturing Same, of which the following description, in connection with the accompanying drawings, is a specification, like reference characters on the drawings indicating like parts in the several figures.

This invention relates to improvements in shoemaking and more particularly to the production of shoe bottoms.

Important objects of this invention are to increase the durability of shoe bottoms and to effect economies in the finishing of shoe bottoms. It has heretofore been the custom to scour off the outer skin from a leather sole, after it has been attached to a shoe, to expose the grain, then buff the grain to smooth it and then frequently to stain, black or paint, and subsequently polish, the surface to produce a pleasing appearance. The present invention has the advantage that no material is removed from the sole leather but all of the material is retained and the wearing qualities of all of that material are enhanced; and that economies are effected which may include the saving of the entire expense of the scouring, buffing, staining or painting and polishing operations and of the materials used in those operations. Other objects and advantages of this invention will appear as the invention is further explained.

In one of its important aspects this invention consists in bottom finishing a leather sole prior to its attachment to the shoe by breaking up its tread surface, by compression, into minute raised and depressed areas in such close proximity to each other as to transform the original natural surface appearance, requiring no scouring or buffing of the sole after the sole is attached to the shoe, and attaching the bottom finished sole to a shoe. In practising this portion of my invention I have found it advantageous to subject a sole to a pressure of from ten to twenty tons per square inch between a pressure plate engaging the flesh side of the sole and an opposed grain side engaging plate or die the working face of which is provided with

a narrow plain border surrounding a slightly raised portion that is corrugated by closely adjacent oblique intersecting grooves reaching to the level of the border and producing pyramidal projections. When a sole is subjected to the described pressure between said plate and die the sole is condensed, the narrow margin rendered hard and smooth, and the area inside of said margin has its surface broken up into closely adjacent raised and depressed faces each of small area by the action of said corrugated area of the die, to transform the unpleasing appearance of the glazed skin of the leather into a finely reticulated pleasing appearance.

To insure the best results, the edges of the sole may be confined during its treatment, whereby spreading of the sole under pressure is prevented or limited and the density of its marginal portion better controlled as well as the size of the finished sole and its edge contour and finish determined with precision. The narrow marginal border provides a place in which a line of nails or stitching may be advantageously placed. This treatment produces a completely bottom finished sole requiring no further finishing treatment after its application to the shoe. The great pressure applied to the sole produces a surface density that renders the surface appearance of the sole substantially unaffected by the treatment to which the shoe is subjected in the usual sole leveling operation.

The improved sole, bottom finished before it is attached to the shoe, is also a part of the invention.

The various aspects and parts of this invention will be more fully understood from the following description and accompanying drawings and will then be particularly pointed out in the claims.

In the drawings:—

Figure 1 is a plan view of a sole after it has been finished by the method of my invention, and prior to its attachment to a shoe;

Fig. 2 is a cross section on the line 2—2 of Fig. 1;

Fig. 3 is a bottom plan view of a shoe with the sole attached thereto; and

Fig. 4 is a perspective view of one form of mold or dies which may be used in practising the method of my invention.

Referring to the drawings, 4 indicates generally a sole embodying the present invention as it appears after it has been bottom finished by my method.

In the practice of my improved method, I find it desirable to put the sole blanks somewhat in temper before operating upon them.

In Fig. 4 of the drawings is shown one form of mold which may be used in the practice of my method, comprising a pressure plate 12 for engaging the flesh side of the sole and an opposed grain side engaging plate or die 14. Suitably formed edge dies 16, 18 are arranged in proper relation to the plate 12 and the die 14 to confine or exert pressure upon the edges of the sole. The surface of the plate 12 may be smooth or formed with any desired design. The surface of the die 14 is formed with a slightly raised interior area 20 corrugated by closely adjacent, oblique, intersecting grooves reaching to the level of a plain, marginal border 22 and producing a series of more or less minute, pyramidal projections.

In practising my method, the sole is placed in the mold and subjected to pressure in a powerful compressing machine. A machine which I have used successfully for this purpose was specially designed and capable of applying to a sole a pressure of as much as 600 tons. The amount of pressure required in practice varies considerably according to the condition and quality of the stock and the size of the sole blank. In order to obtain all the advantages secured by practising the method in the preferred manner, the pressure should be sufficient to render the interior portion of the sole hard and dense and to impart to it a smooth and pleasing surface finish sufficiently hard and durable to be substantially unaffected by any subsequent operations such as sole leveling or molding to be performed upon the shoe. An operator quickly learns to determine from the appearance of the finished sole and the operation of the machine when sufficient pressure is being applied.

By the compression of a sole blank in the manner described, its thread surface is broken up into minute, raised and depressed areas or faces of which the latter are arranged obliquely to the general plane of the face of the sole, and in such close proximity to each other as to transform the original, natural surface appearance of the leather into a pleasing, finished surface appearance, eliminating or concealing surface blemishes and producing a finished sole which will require no scouring, buffing or other bottom finishing after the sole is attached to a shoe.

The reticulated, or corrugated, area of the sole preferably extends over the shank portion to a point slightly in the rear of the breast of the heel, giving a complete bottom finish to the sole.

In order to improve the appearance and finish of the sole, I prefer to leave the marginal portion acted upon by the margin 22 of the grain face engaging die 14 plain or smooth; although this is not absolutely essential to the invention. This plain margin or border is, by the compression, smoothly finished and presents a pleasing appearance, requiring no further finishing, especially when it is traversed by a line of nails 24 or a line of stitches 26, or both, such nails or stitches acting as fastenings for connecting the sole to another part of the shoe.

A rib 23 formed upon the marginal border 22 of the die 14 is arranged to form in the border of the sole face a groove 28 to receive the stitches 26 so that they will not project above the surface of the sole in the finished shoe.

In further detail, I also contemplate, in the practice of my method, attaching the bottom finished sole to a shoe, by nailing or stitching and, thereafter, by the application of pressure, leveling, molding or shaping the sole to the contour of the last. I am able to do this without defacing or losing the surface finish imparted to the sole in the compressing step by reason of the hardness, density and durability of the surface of the compressed blank.

The improved bottom finished sole forming a part of my invention and produced by my method is characterized by a tread face, broken up into raised and depressed surfaces of small area and in such close proximity to each other as to transform the original surface appearance of the leather into a pleasing surface appearance, requiring no scouring or bottom finishing of the sole after it is attached to the shoe. These small depressed areas are preferably arranged obliquely to the general plane of the sole, breaking up the light and producing a uniform, unblemished surface appearance. The smooth marginal border of the sole illustrated in the drawings adds to the pleasing appearance and has its original surface appearance transformed into a pleasing finished effect.

The edges of the sole are shaped, made uniformly smooth and finished by the pressure of the edge dies 16, 18 and may be made so perfect that no edge finishing is required.

It is within the contemplation of my invention to stain, ink or otherwise treat the sole blank prior to compression with any compound or finishing material desired and, when a sole thus treated is finished in accordance with my method, a very attractive result is secured. The stain or finishing preparation may be applied to the sole edge, and the subsequent action of the dies 16, 18 will form and finish the edge to such a degree of perfection that no further finish-

ing treatment is required except, possibly, brushing.

Having described my invention, what I claim as new and desire to secure by Letters Patent of the United States is:—

1. That improvement in methods of making shoes which consists in bottom finishing a leather sole prior to its attachment to the shoe by breaking up its tread surface, by compression, into minute raised and depressed areas in such close proximity to each other as to transform the original natural surface appearance of the leather into a pleasing surface appearance requiring no scouring or buffing of the sole after it is attached to the shoe.
2. That improvement in methods of making shoes which consists in bottom finishing a leather sole prior to its attachment to the shoe by breaking up its tread surface, by compression, into minute raised and depressed areas in such close proximity to each other as to transform the original natural surface appearance of the leather into a pleasing surface appearance requiring no scouring or buffing of the sole after it is attached to the shoe, the compression being sufficient to produce upon the sole a bottom finish sufficiently hard and durable to be substantially unaffected by a subsequent leveling or molding operation.
3. That improvement in methods of making shoes which consists in bottom finishing a leather sole prior to its attachment to the shoe by breaking up its tread surface, by compression, into minute raised areas and relatively depressed areas the faces of which are oblique to the general plane of the sole, said surface being of such density as to be unaffected by a sole leveling operation, and said areas being in such close proximity to each other as to transform the original natural surface appearance of the leather into a pleasing surface appearance requiring no scouring or buffing of the sole after it is attached to the shoe.
4. That improvement in methods of making shoes which consists in bottom finishing a leather sole prior to its attachment to the shoe by compressing fine corrugations into the tread face of the sole except at its margin and compressing the marginal nail or stitch receiving portion of the tread face to lie in the same plane as the corrugated area and to present, when the line of nails or stitches has been applied, a border requiring no further finishing around the margin of the sole bottom.
5. That improvement in methods of making shoes which consists in bottom finishing a leather sole prior to its attachment to the shoe by confining the edge of the sole to control its spreading; compressing fine corrugations into the tread face of the sole except at its margin; and compressing the marginal nail or stitch receiving portion of the tread face to lie in the same plane as the corrugated area and to present, when the line of nails or stitches have been applied, a border of pleasing appearance requiring no further finishing around the margin of the sole bottom.
6. That improvement in methods of making shoes which consists in bottom finishing a leather sole prior to its attachment to the shoe by breaking up the major portion of its tread surface, by compression, into minute raised and depressed areas in such close proximity to each other as to transform the original natural surface appearance of the leather into a pleasing surface appearance, and compressing into the marginal portion of the tread face a groove to receive a line of stitching or fastenings for connecting the sole to another part of the shoe.
7. That improvement in methods of making shoes which consists in bottom finishing a leather sole prior to its attachment to a shoe by treating the sole with a stain or finishing preparation, and thereafter breaking up its tread surface, by compression, into minute raised and depressed areas in such close proximity to each other as to transform the original natural surface appearance of the leather into a pleasing surface appearance requiring no scouring or buffing of the sole after it is attached to the shoe.
8. That improvement in methods of making shoes which consists in bottom finishing a leather sole prior to its attachment to a shoe by treating the edge of the sole with a stain or finishing preparation, thereafter breaking up its tread surface, by compression, into minute raised and depressed areas in such close proximity to each other as to transform the original natural surface appearance of the leather into a pleasing surface appearance requiring no scouring or buffing of the sole after it is attached to the shoe, and subjecting the edge of the sole to compression to produce a well formed and finished edge.
9. As an article of manufacture, a leather sole having the tread face of its forepart and shank embraced by a marginal finished border to receive the sole attaching fastenings and the surface of the interior portion of said tread face broken up by compression into raised and depressed faces of small areas in such close proximity to each other as to transform the original surface appearance of the leather into a pleasing surface appearance requiring no scouring or buffing of the sole after it is attached to a shoe.
10. As an article of manufacture, a leather sole having the tread face of its forepart and shank embraced by a finished marginal border and the surface of the interior portion of said tread face broken up by com-

- pression into raised and depressed faces of small areas in such close proximity to each other so as to transform the original surface appearance of the leather into a pleasing surface appearance requiring no scouring or buffing of the sole after it is attached to a shoe, the planes of said depressed faces being oblique to the plane of the tread face of the sole. 35
- 10 11. As an article of manufacture, a leather sole having stain applied to its tread face and having the forepart and shank portions of its tread face broken up by compression into raised and depressed faces of small areas 40 in such close proximity to each other as to transform the original surface appearance of the leather into a pleasing surface appearance requiring no scouring or buffing of the sole after it is attached to a shoe, the said 45 surface being sufficiently hard and durable to be substantially unaffected by a subsequent leveling or molding operation. 50
12. As an article of manufacture, a leather sole having a finished edge and tread face 55 in the forepart and shank consisting of a stained and hardened edge face, a fastener receiving border around the forepart and shank and the surface inside said border broken up by compression into raised and 60 depressed faces of small areas in such close proximity to each other as to transform the original surface appearance of the leather into a pleasing surface appearance requiring

no scouring or buffing of the sole after it is attached to a shoe. 55

13. As an article of manufacture, a leather sole having a finished tread face on its forepart and shank consisting of a fastener receiving border having a compressed stitch receiving groove and having the surface inside said border broken up by compression into raised and depressed faces of small areas in such close proximity to each other as to transform the original surface appearance of the leather into a pleasing surface appearance requiring no scouring or buffing of the sole after it is attached to a shoe. 40

14. That improvement in methods of making shoes which consists in staining a leather sole and bottom finishing the sole by compression before attaching it to a shoe to break up the natural surface of the leather into a pleasing surface of uneven contour having stained faces that are smoothed and polished by the compression. 55

15. That improvement in methods of making shoes which consists in staining the edges of a sole before the sole is attached to a shoe, confining the edges of the sole and subjecting the sole to compression sufficient to shape 60 the sole and harden and set the stained edge of the sole, then attaching the sole to a shoe and brushing the edge of the sole to polish it.

In testimony whereof I have signed my name to this specification.

THOMAS LUND.

It is hereby certified that in Letters Patent No. 1,282,253, granted October 22, 1918, upon the application of Thomas Lund, of Beverly, Massachusetts, for an improvement in "Shoe-Soles and Processes of Manufacturing Same," an error appears in the printed specification requiring correction as follows: Page 1, line 44, after the syllables "pearance" and before the comma insert the words of *the leather into a pleasing surface appearance*; and that the said Letters Patent should be read with this correction therein that the same may conform to the record of the case in the Patent Office.

Signed and sealed this 14th day of October, A. D., 1919.

[SEAL.]

M. H. COULSTON,
Acting Commissioner of Patents.
